Inventor:

Dr. Wangemann.

UNITED STATES PATENT OFFICE

PAUL WANGEMANN, OF BERLIN, GERMANY

MEANS FOR FASTENING POSTAGE STAMPS IN ALBUMS

Application filed May 9, 1928, Serial No. 276,485, and in Germany June 28, 1927.

The invention relates to means for fastening postage-stamps and the like in albums without employment of the hitherto usual hinges.

The present method has the advantage, that the postage-stamps are not injured by the laps, pasted upon the same.

Fig. 1 illustrates one mode of embodying the present invention in plan.

Fig. 1^a is a side-view of the same.

10 Figs. 2 and 3 show modified methods in top plan.

Figs. 2^a and 3^a are side-views, and

15 Figs. 4 and 4^a illustrate the arrangement in the album.

In Figs. 1 and 1^a, *a* indicates a tape, or strip of transparent material, having two bent over edges *b*, *b*. The postage-stamp *c* is inserted into the said bent over edges and the postage-stamp, together with the corresponding part

20 *d* severed from the tape or strip by the cut *e*—*e*. One or both edges *b* are gummed, so that the postage-stamp *c* can, with the cut-off covering *d*, be directly pasted into the album by means of one of the gummed edges *b*.

25 In the modified mode of embodying the present invention illustrated in Figs. 2 and 2^a, one or both edges are sub-divided into individual teeth *b'*, *b'*, *b''*, *b''*, by incisions. If only single teeth *b'* are pasted upon the

30 album-sheet *g*, the postage-stamp is held in position by the other teeth *b''*, even if the covering *d* is folded entirely upward. In the method according to Figs. 3 and 3^a, a coloured

35 paper strip *h* is gummed on its rear face and is employed as a support, in order to render the appearance of the postage-stamp more prominent. In Fig. 4, the postage-stamp *c* is, with its cover *d*, not pasted upon the album-sheet, but slipped upon a paste-board strip *i*,

40 along which latter it may be displaced. Fig. 4^a shows in plan, how the postage-stamp *c* can be displaced on the strip *i* and how the individual strip *i* can be displaced in its height along the album-sheet *k*, so that the different

45 postage-stamps can be displaced over the entire page of the album-sheet.

I claim:

1. Means for fastening postage-stamps in albums, consisting of a strip of transparent

50 material having one gummed edge bent over.

2. Means for fastening postage stamps in albums, consisting of a strip of transparent material, having two edges bent over.

3. Means for fastening postage-stamps, consisting of a strip of transparent material 55 having two edges bent over embracing a gummed paper strip.

In testimony whereof I have affixed my signature.
